[57] CLAIM

The ornamental design for a motorcycle article carrier,
substantially as shown and described.

DESCRIPTION

FIG. 1 is a top plan view of a motorcycle article carrier
showing the new design;

FIG. 2 is an elevational view of one end thereof;

FIG. 3 is a front elevational view thereof;

FIG. 4 is a bottom plan view thereof;

FIG. 5 is a rear elevational view thereof;

FIG. 6 is an elevational view of the other end thereof;

FIG. 7 is a top plan view of a motorcycle article carrier
showing a second embodiment of the new design, the
sole difference being in the addition of the trim rails;

FIG. 8 is an elevational view of one end of FIG. 7;

FIG. 9 is a front elevational view of FIG. 7;

FIG. 10 is a bottom plan view of FIG. 7;

FIG. 11 is a rear elevational view of FIG. 7; and

FIG. 12 is an elevational view of the other end of FIG.
